UNITED STATES PATENT OFFICE.

JOHN B. WARREN, OF BOLTON, MASSACHUSETTS, ASSIGNOR TO BROADFIELD POULTRY FARM, INC., OF BOLTON, MASSACHUSETTS, A CORPORATION OF MASSACHUSETTS.

TRAY FOR EGG-CASES.

1,230,546.

Specification of Letters Patent. Patented June 19, 1917.

Application filed May 26, 1916. Serial No. 100,709.

To all whom it may concern:

Be it known that I, JOHN B. WARREN, a citizen of the United States of America, and a resident of Bolton, in the county of 5 Worcester and State of Massachusetts, have invented certain new and useful Improvements in Trays for Egg-Cases, of which the following is a specification.

This invention relates to trays for egg 10 cases or crates, and is an improvement upon the tray shown and described in the Letters Patent of the United States No. 1,097,743, issued to me May 26, 1914.

One object of the present invention is to 15 simplify the construction of the tray and at the same time give it greater rigidity when in use than was obtained in the tray shown in the above-mentioned patent.

Another object of the invention is to provide 20 a structure the various units of which may be readily handled in an automatic machine when the various members are assembled to form the tray.

A further object is to provide a tray the 25 construction of which is such that the eggs may be candled without removal from the tray.

The invention consists in certain novel 30 features of construction and arrangement of parts which will be understood by reference to the description of the drawings and to the claims hereinafter given.

For the purpose of illustrating the invention one preferred form thereof is illustrated 35 in the drawings, this form having been found to give satisfactory and reliable results, although it is to be understood that the various instrumentalities of which the invention consists can be variously arranged 40 and organized, and that the invention is not limited to the precise arrangement and organization of these instrumentalities as herein shown and described.

Of the drawings:

45 Figure 1 represents a plan of an egg case containing a tray embodying the features of the present invention.

Fig. 2 represents a partial vertical section of the same on line 2—2 on Fig. 1.

50 Fig. 3 represents a partial vertical section of the same on line 3—3 on Fig. 1.

Fig. 4 represents an elevation of one of the divisional walls.

Fig. 5 represents an elevation of one of

the other divisional walls adapted to be 55 engaged in the slits at the opposite ends of the divisional walls shown in Fig. 4.

Fig. 6 represents an elevation of one of the divisional walls adapted to be engaged in the interior slits of the divisional walls 60 shown in Fig. 4.

Fig. 7 represents an elevation of one of the yielding strips for positioning the larger end of the egg, and

Fig. 8 represents an elevation of one of 65 the inclined strips for positioning the smaller end of the egg.

Similar characters designate like parts throughout the several figures of the drawings.

In the drawings, 10 represents an egg case containing a tray composed of a plurality of partition members or divisional walls 11 having interlocked therewith a plurality of other partition members or divisional walls 12 and 13, these partition members 11, 12, and 13 being shown in elevation in Figs. 4, 5, and 6 respectively. All of these members are preferably constructed of pasteboard or some similar yielding material.

Each partition member 11 is provided with a plurality of slits 14 extending downwardly from the upper edge thereof, and each of said slits having a projection 15 85 extending across the same as clearly shown in Fig. 4 of the drawings. In the construction of the tray only two partition members 12 are used, each of these partition members being provided with slits 16 extending 90 upwardly from the lower edge thereof, and each of these slits being provided with a projection 17 extending across said slit. The two partition members 12 are designed to be interlocked with the partition members 11 and positioned in the outer slits 14 thereof. The intermediate slits 14 of the partition members 11 are adapted to receive the partition members 13, each of which is provided with a plurality of 100 slits 16 extending upwardly from the lower edge thereof, and having a projection 17 extending across each slit. These partition members 13 are provided with a plurality of U-shaped notches 18 of considerable 105 width, as shown in Fig. 6 of the drawings, the bottom of these notches 19 being substantially midway of the height of said par-

tion members, while the side edges 20 thereof are inclined upwardly from each other, all as shown in Fig. 6 of the drawings.

5 The partition members 12 and 13 are each provided with a plurality of alined openings 21 extending therethrough at the same distance from the upper edge of said partition members that the projections 15 are located relatively to the upper edge of the partition members 11. When the various partition members 11, 12, and 13, have been assembled as shown in Figs. 1, 2, and 3 of the drawings, the projections 15 will extend 10 into the openings 21 and lock the partition members 11, 12, and 13 together. In a similar manner, the partition members 11 are each provided with a plurality of alined openings 22 which are adapted to receive the 15 projections 17 in the slits 16 of the partition members 12 and 13, thus more firmly locking the various partition members together.

When these partition members 11, 12, and 13 have been assembled, a plurality of egg 25 receiving pockets are formed, as shown in Figs. 1 to 3 inclusive. The partition members 11, 12, and 13 are made of sufficient height so that the walls of the pockets formed thereby will extend beyond the ends 30 of any eggs positioned therein. The partition members 12 are provided with additional slits 23 in the upper edges thereof, these slits or incisions 23 being adapted to receive a plurality of yielding strips 24. 35 Each strip 24 is provided with an opening 25 therein near either end thereof, which openings when properly positioned in the slits 23 are adapted to receive a locking projection 26 extending into each slit. It is 40 obvious, therefore, that the strips 24 are locked at either end to the outer partition members 12, while the intermediate portions of said strips 24 are positioned within the wide U-shaped notches 18 in the strips 13, 45 and bear against the inclined walls 20 of said U-shaped notches 18.

Each of the partition members 11 is provided with a plurality of inclosed slots 27, these slots being in pairs and inclined down- 50 wardly toward each other, as shown in Fig. 4 of the drawings. Each pair of slots 27 is located between the slits or incisions 14. Each inclosed slot 27 is provided with an inwardly extending projection or locking 55 member 28. In the slots 27 are positioned a plurality of strips 29, each strip being provided with a plurality of openings 30 there- through.

When the strips 29 have been positioned 60 in the slots 27 of the partition members 11, each opening 30 in said strips will receive one of the locking projections 28 and thereby prevent end movement of said strips. Both of the strips 24 and 29 are made of 65 yielding material, such as pasteboard, and

when said strips have been positioned in the slits 23 or slots 27 provided therefor, said strips 24 will be perpendicular to the strips 29 and removed from the walls of the pockets formed by the interlocked partition members 11, 12, and 13. The lower strips 29 when positioned will be inclined downwardly toward each other as indicated in Fig. 2 of the drawings, and each pair of said strips is adapted to receive and position the smaller 70 end of an egg 31, while the upper end of said egg will be positioned between the strips 24 at a higher level than the strips 29.

When the egg is inserted between the strips 24 they will be bent from each other, 80 as shown in Fig. 1, conforming to the shape of the egg, the strips 24 also becoming somewhat curved over the larger end of the egg, as indicated at 32 in Fig. 3 of the drawings.

Each strip 24 and 29 is provided with oppositely disposed notches 33 at one end, which facilitates the removal of the strips when such removal is desired in order to remove the eggs from the tray. These notches 33 in the strips 24 also facilitate the assembling of the various units of the tray by means of automatic machinery designed for this purpose.

One of each pair of slits 23 is wider than the other, as shown at 34 in Fig. 5 of the drawings. The object of making these particular slits of greater width as shown is to facilitate the quick removal of one of each pair of strips 24 when it is desired to remove the eggs 31 from the pockets of the 100 tray, it being possible to remove all the eggs without displacing the other strip 24 of each pair.

By constructing the tray in the manner described, the various parts may be quickly 105 assembled in automatic machines, and the completed tray delivered therefrom in condition for immediate use.

By providing the interior strips 13 with the wide notches 18, the eggs contained in 110 the tray may be candled without handling and without removal from the tray.

The various members constituting the tray are locked together in such a manner that none of the parts will be displaced accidentally.

It is believed that the operation and many advantages of this invention will be fully understood from the foregoing description.

Having thus described my invention, I claim:

1. In a device of the class described, the combination of a collapsible tray having a plurality of egg receiving pockets; means 125 within each pocket consisting of flat yielding strips extending at different levels across said pockets at right angles to each other and adapted to centrally position an egg free from contact with the walls of said 130

pockets, said strips having ends extending beyond the outer walls of said tray; and means for locking said strips to said walls.

2. In a device of the class described, the 5 combination of a collapsible tray having a plurality of egg receiving pockets formed of a plurality of interlocked divisional walls having slots each provided with an inwardly extending projection; and means 10 within each pocket consisting of two pairs of flat yielding strips extending across said pockets at right angles to each other and at different levels adapted to centrally position an egg free from contact with the walls of 15 said pockets, said strips being provided with openings each adapted to receive one of said projections.

3. In a device of the class described, the combination of a collapsible tray having a 20 plurality of egg receiving pockets; means within each pocket consisting of two pairs of flat yielding strips extending across said pockets at right angles to each other and at different levels adapted to centrally position 25 an egg free from contact with the walls of said pockets; means for locking said strips to said walls; and oppositely disposed notches at one end of each of said strips.

4. In a device of the class described, the 30 combination of a collapsible tray having a plurality of egg receiving pockets formed of a plurality of interlocked divisional walls having slots each provided with an inwardly extending projection; means within each 35 pocket consisting of two pairs of flat yielding strips extending across said pockets at right angles to each other and at different levels adapted to centrally position an egg free from contact with the walls of said 40 pockets, said strips being provided with openings each adapted to receive one of said projections; and oppositely disposed notches at one end of each of said strips.

5. In a device of the class described, the 45 combination of a collapsible tray having a plurality of egg receiving pockets formed of a plurality of interlocked divisional walls perpendicular to each other, one set of said walls having at one level a plurality of 50 inclosed slots and the outer walls of the other set having open slots at a higher level; a pair of strips extending across each row of pockets and locked at their ends in said open slots; and another pair of strips extending 55 across each row of pockets at right angles to the beforementioned strips, and locked in the inclosed slots of said divisional walls through which they extend.

6. In a device of the class described, the 60 combination of a collapsible tray having a plurality of egg receiving pockets formed of a plurality of interlocked divisional walls perpendicular to each other, one set of said walls having at one level a plurality of 65 inclosed slots inclined downwardly toward

each other and the outer walls of the other set having open slots at a higher level; a pair of strips extending across each row of pockets and locked at their ends in said open slots; and another pair of strips extending across each row of pockets at right angles to the beforementioned strips and locked in the inclosed slots of said divisional walls through which they extend.

7. In a device of the class described, the 75 combination of a collapsible tray having a plurality of egg receiving pockets formed of a plurality of interlocked divisional walls perpendicular to each other, one set of said walls having at one level a plurality of inclosed slots inclined downwardly toward each other and each provided with an inwardly extending projection and the outer walls of the other set having open slots at a higher level and each provided with an 80 inwardly extending projection; a pair of strips extending across each row of pockets and provided at their ends with openings adapted to receive the projections in said 85 open slots; and another pair of strips extending across each row of pockets at right angles to the beforementioned strips and provided with a plurality of openings adapted to receive the projections in the inclosed 90 slots of said divisional walls through which 95 they extend.

8. In a device of the class described, the combination of a collapsible tray having a plurality of egg receiving pockets formed of a plurality of interlocked divisional walls 100 perpendicular to each other, one set of said walls having at one level a plurality of inclosed slots and the outer walls of the other set having open slots at a higher level, while the intermediate walls of the latter set are 105 provided with U-shaped notches in their upper edges adapted to receive and support both upper strips extending through each row of pockets; a pair of strips extending across each row of pockets and locked at 110 their ends in said open slots; and another pair of strips extending across each row of pockets at right angles to the beforementioned strips and locked in the inclosed slots of said divisional walls through which they 115 extend.

9. In a device of the class described, the combination of a collapsible tray formed of two sets of divisional walls perpendicular to each other having aligned openings therein, 120 one set of walls having a plurality of parallel slits from the upper edge thereof and the other set having similar slits in the lower edge with the interior walls of the last mentioned set also provided at their upper edges 125 with wide U-shaped notches extending substantially to the center of said walls; and a locking projection in each slit adapted to be positioned in one of said openings.

10. In a device of the class described, the 130

- combination of a collapsible tray formed of two sets of divisional walls perpendicular to each other having aligned openings therein, one set of walls having a plurality of parallel slits from the upper edge thereof and the other set having similar slits in the lower edge with the interior walls of the last mentioned set also provided at their upper edges with wide U-shaped notches extending substantially to the center of said walls and having the upwardly extending edges thereof inclined from each other; and a locking projection in each slit adapted to be positioned in one of said openings.
11. In a device of the class described, the combination of a collapsible tray having a plurality of egg receiving pockets; means within each pocket consisting of two pairs of flat yielding strips extending across said pockets at right angles to each other and at different levels adapted to centrally position an egg free from contact with the walls of said pockets; and means for locking said strips to said walls while permitting slight end movement of said strips.
12. In a device of the class described, the combination of a collapsible tray having a plurality of egg receiving pockets; means within each pocket consisting of two pairs of flat yielding strips extending at different levels across said pockets at right angles to each other and adapted to centrally position an egg free from contact with the walls of said pockets; and locking means on said walls coacting with said strips adapted to prevent the accidental displacement of said strips while permitting limited end movement thereof.
13. In a device of the class described, the combination of a collapsible tray having a plurality of egg receiving pockets; means within each pocket consisting of two pairs of flat yielding strips extending at different levels across said pockets at right angles to each other and adapted to centrally position an egg free from contact with the walls of said pockets, said strips having their ends extending beyond the outer walls of said tray and provided with oppositely disposed notches in the edges thereof; and means on said walls coacting with openings in said strips whereby the accidental displacement of said strips is prevented while limited end movement thereof is permitted.

Signed by me at 4 Post Office Sq., Boston,
Mass., this 22nd day of May, 1916.

JOHN B. WARREN.
